SET OF HIGH SPEED CARBIDE CHASERS

James A. Scott, Pittsburgh, Pa., and Donald O. Appleby, Mentor, Ohio; said Appleby assignor to The Pipe Machinery Company, Wickliffe, Ohio, a corporation of Ohio, and said Scott assignor to United States Steel Corporation, a corporation of New Jersey

Filed Nov. 1, 1962, Ser. No. 234,752

1 Claim. (Cl. 10—120)

This invention relates to high speed carbide thread cutting teeth for cutting external threads of the general character disclosed in the applications of Donald O. Appleby, Serial No. 234,751, filed November 1, 1962, and Serial No. 234,753, filed November 1, 1962. For convenience in comparison therewith, it is shown herein as embodied in a set of three chasers of two teeth each for cutting external tapered threads having a 45° forward flank angle, a 0° rear flank angle, and flat crests and roots, its use in a set of chasers of a different number and with a different number of teeth, and for cutting cylindrical threads and for tapping being apparent from the illustrative example.

As therein more fully disclosed, the problem presented in the forming of threads at high speed with carbide chasers is the result of a combination of factors. First, generally, carbide chasers should make a positive cut at all times. Second, they are very brittle and tend to break unless properly loaded. Thirdly, due to the high speed, loading with chips must be avoided and free access of coolant must be permitted. These latter problems are difficult of solution because of the rapid accumulation of chips at high speed and the resultant high heat developed. Loading of chips tends not only to greatly increase the stress load on the chaser teeth and the power requirements for forcing the teeth on their cutting strokes, it also results in the coolant used being dissipated largely on already formed chips and not reaching as effectively as desired the teeth and the metal at the cutting edges of the teeth. The problem, therefore, is to cut at high speeds while providing ample space for chips and their ready removal by the coolant, without packing, and to assure that the final surfaces originally cut by the teeth are not marred by chips or rubbed by succeeding teeth in any way thereafter.

The manner in which these combined results are obtained will become apparent from the following description, wherein reference is made to the drawings, in which.

FIG. 1 is a diagrammatic front elevation of the rotary spindle head with the set of chasers of the present invention installed therein;

FIGS. 2 and 3 are an elevation of the forward face, and a left end elevation, respectively, of the first operating chaser of the set;

FIGS. 4 and 5 are a front elevation of the forward face, and a left end elevation, respectively, of the second chaser of the set;

FIGS. 6 and 7 are a front elevation of the forward face, and a left end elevation, respectively, of the third chaser of the set;

FIG. 8 is an enlarged diagrammatic illustration showing, in superposed relation, the cuts made by the various teeth of the chasers of the set; and

FIGS. 9A through 9F are enlarged fragmentary illustrations showing the cuts made by the teeth, respectively.

Referring to the drawings, the chasers are indicated at C₁, C₂, and C₃, and the teeth, in cutting sequence, as 1 through 6, respectively.

The first chaser is illustrated in FIGS. 2 and 3 at C₁, this chaser having teeth 1 and 4, respectively. The next chaser, in order of operation, is illustrated in FIGS. 4 and 5, and indicated at C₂, and has teeth 2 and 5, respectively.

The third chaser, in order of operation, is illustrated in FIGS. 6 and 7, at C₃, and has teeth 3 and 6, respectively.

Again referring to the drawings, the chasers are shown as mounted in a rotary spindle head 1 which is power driven for rotating the chasers about the common axis. The teeth of the chasers are arranged so that, in cutting sequence, the tooth 1 makes the first cut, indicated at 10, including a root portion 11, and an elongated leading portion 12. The first cut has flank ends 13 and 14, respectively. Since this tooth is of a relatively limited depth from its base to its crest, it can easily be made sturdy to resist the cutting stresses and can effectively make the cut despite the long length of the shear line and the depth of the portion 11, while providing ample space for removal of chips. It is noted that the flank ends 13, 13a, and 14 do not make a cut to the finished flank lines, indicated in dotted lines, of the thread.

The second cut is formed by tooth 2. This tooth plunges deeply into the metal toward the finished root line of the thread, as indicated at 15. This plunging cut has flank ends 16 and 17, the end 16 forming a continuation of the shear line on the forward flank formed by the preceding tooth 1, the flank end 17 being inset away from the rear flank line. The next cut, made by tooth 3, is indicated at 18. This cut has flank ends 19 and 20 and root surface 21. The root surface 21 cuts to the root line of the finished thread for a substantial portion of the length of the root line in a direction endwise of the axis of the thread. The surface 19 forms a continuation of the surface 16 formed by the cut 15, and the surface 20 is inset away from the flank cut 17. Thus along the surface exposed at the leading flank of the thread, between adjacent teeth, the leading flank of the tooth 2 rubs against the surface 13a and, in turn, the tooth 3 rubs against the forward flank surfaces 13a and 16. While this is objectionable, the teeth do have very substantial lengths, endwise of the thread axis in relation to their dimensions radially or toward the root of the thread. At the same time, ample space is provided for accumulation and escape of chips.

Having made three successive plunging cuts, the next, or fourth, cut is by the tooth 4 on the chaser C₁. This cut is a simple flank cut, as indicated at 22. The fifth cut is made by tooth 5 of chaser C₂ and is another flank cut, indicated at 23. Thus far none of the finished surfaces of the thread have been formed, except the root.

The last one or sixth cut 24a, 24b, and 24c, is an interrupted flank cut, including the portion 24a on the forward flank and the portion 24b on the rear flank, and the portion 24c on the crest of the trailing tooth. The 50 cut, indicated at 25, also includes portions 24d and 24e of the root between the adjacent thread flanks.

As a result of this structure, a quick plunge cut in three successive steps can be made entirely to the root of the thread, the last plunge finishing most of the root. While each of these cuts removes a substantial amount of material, adequate space for the chips to be flushed out by coolant at each cut is provided. Furthermore, no portion of the final surface of the thread, except the root, is in any manner engaged by a tooth after the initial formation 60 of the thread surface. The final cut has a long interrupted shear line, but nevertheless adequate space to permit the coolant to flush away chips is provided. Each tooth can be large, and long lengthwise of the thread axis, and thus be strong enough to withstand the cutting stress imposed by the long shear line.

It has been found that, with this structure, considerable increase in life and improvement in quality can be obtained over the speed and quality obtained by the structure of the above identified application.

The sets of chasers herein are for cutting threads having a wide crest and wide root, as distinguished from

conventional V-shaped threads which have relatively sharp crests and narrow roots, for instance, such as produced by the intersection of planar flanks at 60° to each other, and the words "wide crest, wide root" as used in the claims in referring to the threads are meant to exclude the conventional V-shaped threads, inasmuch as the problems in connection with the latter are totally different from those in connection with the wide crest, wide root type of threads.

Having thus described our invention, we claim:

A set of thread cutting chasers, said set consisting of three high speed carbide chasers each with two teeth only, said chasers being adapted to be mounted in a rotary spindle head in radially and circumferentially spaced relation to each other about the axis of rotation of the head for co-rotation of the chasers by the head about said axis and for concurrent advancement and retraction of the chasers relative to the axis for cutting on a cylindrical member, coaxial with the spindle head, of an external wide crest, wide root, tapered thread, said chasers having their teeth shaped and arranged in the order of cutting as follows:

1st, 2nd, and 3rd teeth with said first tooth having a trailing portion and a leading portion of less height than the trailing portion, the radial heights of said trailing portion, the 2nd tooth, and the 3rd tooth, respectively, being, in the order enumerated, progressively shorter in a direction endwise of the axis and progressively greater in height radially of the axis, and having trailing flanks inset progressively relative to each other, leading flanks sloping inwardly from base to crest so that the axially innermost point on the leading flank of each is coincident with the axially outermost point of its successor, for making 1st, 2nd, and 3rd root cuts, respectively, with the trailing flanks of each root cut stepped inwardly axially of the thread groove from that of its predecessor, and with the leading flanks of the root cuts forming a continuous surface sloping in the trailing direction from crest to trough of the thread, the major portion of the crest of the 3rd tooth conforming to the major portion of the finished root line of the thread, the flanks of the 1st tooth being inset from the finished flank lines of the thread;

a. 4th tooth which is of a height greater than that of said trailing portion of the 1st tooth and less than that of the 2nd tooth, and having a trailing flank inset from the trailing flanks of said 2nd tooth and said portion of the 1st tooth and having a leading flank passing through a point between the radially innermost and outermost ends of the leading flank of the 2nd tooth and sloping from the crest of the 4th tooth in the leading direction toward the base

of the 4th tooth so as to lie forwardly from said point and from the leading flank of said trailing portion of the first tooth throughout the radial extent of said leading flank of the 1st portion, for making an uninterrupted flank cut on the trailing flank only of the thread;

a 5th tooth of greater height than that of the 2nd tooth and less than that of the 3rd tooth, and having a trailing flank inset from the trailing flank of the 1st, 2nd, 3rd and 4th teeth and a leading flank sloping in the leading direction from its crest toward the base of the 5th tooth and intersecting the leading flank of the 3rd tooth so as to lie forwardly of the leading flank of the 4th tooth, for making a second uninterrupted flank cut on the leading flank only of the thread;

a 6th tooth of substantially the same height as the 3rd tooth and having leading and trailing flanks outset, endwise of the axis, from the corresponding flanks of said trailing portion of the 1st tooth and from the corresponding flanks of the 2nd through 5th teeth, and conforming to the finished trailing and leading flanks, respectively, of the finished thread, said 6th tooth having a trailing portion extending in the trailing direction from the lowest point on its rear flank predominantly endwise of the axis and forming with the rear flank of the 6th tooth a continuous cutting edge conforming to the finished leading flank and contiguous crest of the thread, and said leading portion of the 1st tooth extending from the lowest point on the leading flank of the trailing portion of the 1st tooth in the leading direction generally endwise of the axis and forming with the leading flank of said trailing portion a continuous cutting edge extending in the leading direction beyond the leading flank of the thread and being of a radial height less than the height of the trailing portion of the 6th tooth, for making a true-up cut in strata of the pipe outwardly beyond the thread, so that the 3rd tooth makes the final cut on at least the major portion of the thread trough and the 6th tooth makes the finish cut of the remainder of the thread.
